We claim the ornamental design for lighted corner waterfall for a spa or pool, as shown and described.

DESCRIPTION

FIG. 1 is a top plan view of a lighted corner waterfall for a spa or pool, showing our new design;

FIG. 2 is a side elevational view thereof;

FIG. 3 is an enlarged, fragmentary perspective view thereof; and,

FIG. 4 is a cross-sectional view thereof, taken along line 4—4 of FIG. 1.

The broken line showing in the views is for illustrative purposes only and form no part of the claimed design.
